Philip H. Tracy 46 George W. Swift, Jr.,
Joseph C. Gal. 46 by Nathan E. Briggs,
Attorney.

UNITED STATES PATENT OFFICE.

GEORGE WILLIAM SWIFT, JR., OF BORDENTOWN, NEW JERSEY.

PAPER RECEPACLE.

1,158,581.

Specification of Letters Patent.

Patented Nov. 2, 1915.

Application filed September 26, 1913. Serial No. 792,026.

To all whom it may concern:

Be it known that I, GEORGE WILLIAM SWIFT, Jr., a citizen of the United States, residing at Bordentown, in the county of 5 Burlington and State of New Jersey, have invented a certain new and useful Improvement in Paper Receptacles, whereof the following is a specification, reference being had to the accompanying drawing.

10 My invention relates to receptacles each including two plain concentric tubes with corrugated paper between them. As heretofore constructed such receptacles are of two general types, first, a tube formed of 15 spirally wrapped strips and consequently having seams extending transversely with respect to the tube axis from end to end thereof; and second, a tube including two convolutions of corrugated paper so constructed and arranged that their corrugations are held out of mesh with respect to 20 each other.

My invention provides a receptacle adapted for use as a bottle wrapper, including a 25 tube which may be formed without the employment of the spiral winding mechanism which is essential to the formation of said first type of receptacles, and which is more compact and efficient than said second type 30 of receptacles in that the corrugated web constituents thereof are intermeshed.

As hereinafter described, my invention includes a cylindrical tubular paper receptacle comprising two plain concentric cylindrical tubes with two corrugated paper webs between them; the outer and inner tubes being both formed of a single web of plain paper carrying said two corrugated paper webs respectively upon its opposite 40 faces; said two corrugated webs each having their corrugations uniformly spaced, but so respectively differently spaced, circumferentially, that the crests of the corrugations of the respective webs intermesh 45 when said webs are wrapped in concentric relation; said outer and inner tubes being respectively continuous, without transverse seams, from end to end thereof.

As hereinafter described I prefer to attach 50 said corrugated webs to each other, and to the primarily plane webs which carry them, by means at the crests of the corrugations only; said webs remaining separate from each other between said crests, and, 55 therefore, it is to be noted that such a

product and process is claimed in Letters Patent of the United States 1,032,789 granted to me July 16, 1912; the claims of the present case being limited to the construction and arrangement of such a product as a receptacle, and specifically a bottle wrapper.

My invention includes the various novel features of construction and arrangement hereinafter more definitely specified.

In said drawing: Figure I is an end view of a paper receptacle bottle wrapper conveniently embodying my invention in its most complex form, including two corrugated paper webs connected only at the 60 crests of their corrugations and a single plain web carrying both of said corrugated webs. Fig. II is an end view of a paper receptacle bottle wrapper embodying a modified form of my invention, including 65 two corrugated paper webs connected only at the crests of their corrugations and two plain webs respectively carrying said corrugated webs. Fig. III is a longitudinal sectional view of the form of my invention 70 shown in Fig. I provided with double flanged cap closures at its respectively opposite ends. Fig. IV is an end view of a modified form of my invention including 75 two corrugated paper webs connected only at the crests of their corrugations and two plain webs respectively carrying said corrugated webs. Fig. V is an end view of the form of my invention 80 shown in Fig. II provided with double flanged cap closures at its respectively opposite ends. Fig. VI is an end view of a modified form of my invention including 85 a single plain web forming both the inner and outer concentric plain tubes and carrying a single corrugated web between them. Fig. VII is an end view of the form of my invention 90 shown in Fig. III provided with double flanged cap closures at its respectively opposite ends. Fig. VIII is an end view of the form of my invention 95 shown in Fig. IV provided with double flanged cap closures at its respectively opposite ends. Fig. IX is an end view of the form of my invention 100 shown in Fig. V provided with double flanged cap closures at its respectively opposite ends. Fig. X is an end view of the form of my invention 105 shown in Fig. VI provided with double flanged cap closures at its respectively opposite ends.

Referring to the form of my invention 110 shown in Figs. I, III and VI; the single plain and primarily plane web 1 is volutely wrapped to form both the outer cylindrical tube 2 and the inner cylindrical tube 3 which are in concentric relation as shown in Fig. I.

Said single web of plain paper 1 carries the two corrugated paper webs 5 and 6 respectively upon its opposite faces, as best shown in Fig. VI, and attached thereto only at the 5 crests of their corrugations. Said two corrugated webs each have their corrugations uniformly spaced but so respectively differently spaced, that the crests of the corrugations of the respective webs 5 and 6 10 intermesh when said webs are wrapped in concentric relation; the corrugations of the web 5 having a greater circumferential pitch than the corrugations of said web 6. It may be observed that the blank portion 8 of said 15 web 1 between said webs 5 and 6, as shown in Fig. VI, connects the outer and inner cylindrical tubes 2 and 3 as shown in Fig. I and that the opposite ends 9 and 10 of said single web 1 respectively overlap the outer 20 surface of the tube 2 and the inner surface of the tube 3.

The hollow cylindrical receptacle shown in Fig. I may be used as a wrapper with its opposite ends open; but I prefer to provide 25 it at each end with a closure including cylindrical flanges in integral relation respectively arranged to fit outside of the outer tube and inside of the inner tube. As shown in Fig. III the cap 12 includes the two concentric cylindrical flanges 13 and 14 in unitary relation, being formed of a single piece 30 of paper which is pressed to the shape shown, including the diaphragm 15 extending transversely with respect to the receptacle and 35 closing the end thereof. It may be observed that said diaphragm is so constructed and arranged in its relation with said flange 14 as to resiliently oppose endwise movement of the contents of the receptacle and support 40 said contents in spaced relation with the surface upon which the receptacle rests. The opposite end of said receptacle shown in Fig. III has the closure cap 17 including two concentric cylindrical flanges 18 and 19, formed 45 of distinct pieces of paper, respectively arranged to fit outside of the outer tube 2 and inside of the inner tube 3 and including diaphragms 20 and 21 extending transversely with respect to the receptacle and closing the 50 end thereof. Said two pieces of paper forming the cap 17 have adhesive means 23 integrally connecting them. However, it is to be understood that they may be otherwise connected, for instance by a wire staple or 55 eyelet.

In the form of my invention shown in Figs. II and VII; the outer and inner plain cylindrical tubes 25 and 26 are respectively formed by distinct pieces of paper respectively carrying the corrugated webs 28 and 29 which are attached thereto only at the crests of their corrugations as shown in Fig. VII. Said corrugated webs 28 and 29 are of 60 respectively different circumferential pitch, like the webs 5 and 6 aforesaid, so that their

crests intermesh as shown in Fig. II. I prefer to connect said corrugated webs 28 and 29 only by means at the crests of their corrugations. It may be observed that the end 31 of the plain paper web 25 shown in Fig. VII overlaps the outer surface of the outer tube as shown in Fig. II and that the end 32 of the plain paper web 26 shown in Fig. VII overlaps the inner surface of the inner tube as shown in Fig. II.

It is to be understood that the receptacle shown in Fig. II may be provided with closure caps at its opposite ends such as shown in Fig. III.

Referring to the form of my invention shown in Figs. IV and VIII the outer and inner plain cylindrical tubes 35 and 36, shown in Fig. IV, are formed by the single plane paper web 37 shown in Fig. VIII which carries the single corrugated web 38 attached thereto only at the crests of its corrugations. It may be observed that the end 40 of said plane web 37 shown in Fig. VIII overlaps the outer surface of the outer tube 35 as shown in Fig. IV, and the opposite end 41 of said web 37 shown in Fig. VIII overlaps the inner surface of the inner tube 37 as shown in Fig. IV. The blank portion 42 of said web 37 connects the outer and inner cylindrical tubes 35 and 36 as shown in Fig. IV.

Referring to the form of my invention shown in Figs. V and IX; the outer and inner cylindrical tubes 45 and 46 are formed by distinct pieces of paper holding between them the single corrugated web 47 which is primarily carried by the plane web 45 shown in Fig. IX and attached thereto only at the crests of its corrugations. It may be observed that the end 48 of said web shown in Fig. IX overlaps the outer surface of the outer tube 45 shown in Fig. V, and that the end 50 of the plane web 46 shown in Fig. IX overlaps the inner surface of the inner tube shown in Fig. V.

It is to be understood that both forms of my invention shown respectively in Figs. IV and V may be provided with flanged closure caps such as shown in Fig. III.

It is to be particularly noted that each form of my invention above described may be constructed by merely wrapping the fabric cylindrically, and without seams extending transversely with respect to the axis of the receptacle, the several seams being parallel with said axis.

I do not desire to limit myself to the precise details of construction and arrangement herein set forth as it is obvious that various modifications may be made therein without departing from the essential features of my invention as defined in the appended claims.

I claim:—

1. A cylindrical tubular paper receptacle including two plain concentric cylindrical

- 5 tubes with two corrugated paper webs between them; said outer and inner tubes being both formed of a single web of plain paper carrying said two corrugated paper webs respectively upon its opposite faces and attached thereto only at the crests of their corrugations; the corrugated paper on one side of said strip being coextensive with one-half of the length of said strip and the corrugated paper on the other side of said strip being coextensive with the other half of the length of said strip; said two corrugated webs each having their corrugations uniformly spaced, but so respectively differently spaced, circumferentially, that the crests of the corrugations of the respective webs intermesh when said webs are wrapped in concentric relation; said outer and inner tubes being respectively continuous, without transverse seams, from end to end thereof. 10

10 2. A cylindrical tubular paper receptacle including two plain concentric cylindrical tubes with two corrugated webs between them; said outer and inner tubes being formed of a single web of plain paper carrying said two corrugated paper webs upon its opposite faces; the corrugated paper on one side of said strip being coextensive with one-half of the length of said strip and the corrugated paper on the other side of said strip being coextensive with the other half of the length of said strip; said two corrugated webs each having their corrugations uniformly spaced, but so respectively differently spaced, circumferentially, that the crests of the corrugations of the respective webs intermesh when said webs are wrapped in concentric relation; said outer and inner tubes being continuous. 15

15 3. A tubular paper receptacle including two plain concentric tubes with two corrugated webs between them; said outer and inner tubes being formed of a single web of plain paper carrying said two corrugated paper webs upon its opposite faces; the corrugated paper on one side of said strip being coextensive with one-half of the length of said strip and the corrugated paper on the other side of said strip being coextensive with the other half of the length of said strip; said two corrugated webs each having their corrugations uniformly spaced, but so respectively differently spaced, circumferentially, that the crests of the corrugations of the respective webs intermesh when said webs are wrapped in concentric relation; said outer and inner tubes being continuous. 20

20 4. A tubular paper receptacle including two plain concentric tubes with two corrugated webs between them; said outer and inner tubes being formed of a single web of plain paper carrying said two corrugated paper webs upon its opposite faces; the corrugated paper on one side of said strip being coextensive with one-half of the length of said strip and the corrugated paper on the other side of said strip being coextensive with the other half of the length of said strip; said two corrugated webs each having their corrugations uniformly spaced, but so respectively differently spaced, circumferentially, that the crests of the corrugations of the respective webs intermesh when said webs are wrapped in concentric relation; said outer and inner tubes being continuous. 25

25 5. A tubular paper receptacle including two plain concentric tubes with two corrugated webs between them; said two corrugated webs each having their corrugations uniformly spaced, but so respectively differently spaced, circumferentially, that the crests of the corrugations of the respective webs intermesh when said webs are wrapped in concentric relation; said outer and inner tubes being continuous, without transverse seams, from end to end thereof. 30

30 6. A tubular paper receptacle including two plain concentric tubes with two intermeshed corrugated webs between them; said two corrugated webs each having their corrugations uniformly spaced, but so respectively differently spaced, circumferentially, that the crests of the corrugations of the respective webs intermesh when said webs are wrapped in concentric relation; said outer and inner tubes being continuous, without transverse seams, from end to end thereof. 35

35 7. A tubular paper receptacle including two plain concentric tubes with two intermeshed corrugated webs between them; said two corrugated webs each having their corrugations uniformly spaced, but so respectively differently spaced, circumferentially, that the crests of the corrugations of the respective webs intermesh when said webs are wrapped in concentric relation. 40

40 8. A paper receptacle including two plain concentric tubes with a corrugated web between them; said outer and inner tubes being both formed of a single web of plain paper carrying said corrugated paper web and attached thereto only at the crests of its corrugations. 45

45 9. A paper receptacle including two plain concentric cylindrical tubes with two corrugated webs between them; said two corrugated webs having their corrugations so differently spaced circumferentially that the crests of the corrugation of the respective webs intermesh when said webs are wrapped in concentric relation; said outer and inner tubes being respectively continuous, without transverse seams, from end to end thereof. 50

50 10. A paper receptacle including two plain concentric tubes with two corrugated webs between them; said two corrugated webs having their corrugations so differently spaced circumferentially that the corrugations of the respective webs intermesh when said webs are wrapped in concentric relation; said outer and inner tubes being respectively smoothly continuous, from end to end thereof. 55

55 11. A paper receptacle including two plain concentric cylindrical tubes with two intermeshed corrugated webs between them; said

two corrugated webs having their corrugations so differently spaced circumferentially that the corrugations of the respective webs intermesh when said webs are wrapped in 5 concentric relation.

12. A paper receptacle including two plain concentric tubes with two corrugated webs between them; said two corrugated webs having their corrugations so differently spaced circumferentially that the crests of the corrugations of the respective webs intermesh when said webs are wrapped in concentric relation.

13. A tubular paper receptacle including 15 two plain concentric tubes with two corrugated webs between them; said outer and inner tubes being formed of a single web of paper carrying said two corrugated paper webs upon its opposite faces; said two 20 corrugated webs each having their corrugations uniformly spaced, but so respectively differently spaced, circumferentially, that the crests of the corrugations of the respective webs intermesh when said webs are 25 wrapped in concentric relation.

14. A paper receptacle including two smoothly cylindrical and concentric tubes with a corrugated web between them; said outer and inner tubes being both formed of 20 a single web of plain paper carrying said

corrugated paper web and attached thereto at the crests of its corrugations.

15. A cylindrical tubular paper receptacle including two webs with respective corrugations extending parallel with the axis of 35 said tube and intermeshed; said corrugations being differently spaced circumferentially in the different webs, so that the crests of the corrugations intermesh when said webs are wrapped in concentric relation; 40 and means, distinct from said webs, holding them in such differential spaced relation.

16. A cylindrical tubular paper receptacle including two webs with respective corrugations extending parallel with the axis of 45 said tube and intermeshed; said corrugations being differently spaced circumferentially in the different webs, so that the crests of the corrugations intermesh when said webs are wrapped in concentric relation; 50 and means, holding them in such differential spaced relation.

In testimony whereof, I have hereunto signed my name at Bordentown, New Jersey, this nineteenth day of September, 1913. 55
